UNITED STATES PATENT OFFICE.

GEORGE A. HALL, OF PORTLAND, MAINE.

TROLLEY.

SPECIFICATION forming part of Letters Patent No. 597,848, dated January 25, 1893.

Application filed February 6, 1897. Serial No. 622,254. (No model.)

To all whom it may concern:

Be it known that I, GEORGE A. HALL, a citizen of the United States, residing at Portland, in the county of Cumberland and State 5 of Maine, have invented certain new and useful Improvements in Trolleys; and I do hereby declare the following to be a full, clear, and exact description of the invention, such as will enable others skilled in the art to which it applies 10 to make and use the same.

The object of this invention is to improve the overhead trolley by providing one in which the stock of the grooved roller is swiveled to the head of the trolley-pole to provide 15 a pivotal movement which will allow the roller to properly traverse the wire, particularly in turning curves.

Heretofore in making a switch or curve with the rigid trolley the roller takes the wire 20 at an angle and frequently fails to engage the right wire at the switch, also increasing the wear on the wire at this point. With my invention these objectionable features are overcome without affecting the general work 25 of the trolley.

In the accompanying drawings, forming a part of this specification, Figure 1 is a side elevation of a trolley constructed in accordance with my invention. Fig. 2 is a vertical 30 sectional view. Fig. 3 is a rear elevation.

1 indicates the head of the trolley-pole, which is provided at its lower end with the usual socket and at its upper end is formed into an annular flange 2, surrounding an 35 axial recess 3. On one side of the head is an integral bracket 4, forming one of the bearings for two pulleys or guide-rollers 5, hereinafter more particularly referred to.

The upper end of the annular flange 2 is 40 exteriorly threaded to be engaged by the cap 6, the upper part of which is squared to receive a nut-wrench for screwing and unscrewing the said cap. Centrally this cap has a vertical opening which receives the shank 7 45 of the stock of the grooved roller or trolley, the lower end of said shank being reduced to fit in the axial bearing. Upon this stock and within the annular flange 2 is secured a disk 8 by means of the transverse pin 9, said disk 50 having an arm 10, which projects through a slot therefor in the said annular flange. Interposed between this disk and an annular

groove in the head are a series of friction rollers or balls 11, which provide for an easy pivotal movement of the stock. The upper 55 part of the stock is preferably curved rearward, as shown, and bifurcated to receive the grooved roller 12, having an axle journaled in bearings near the end of said bifurcated members. The ends of this axle lie flush with 60 the outer surface of the stock, said axle being held in place by spring-plates 13, secured at their lower ends to the stock by rivets 14 and having notches at their upper end adapted to be sprung into engagement with lugs 15, projecting 65 from the stock. These plates hold the axle of the trolley or grooved roller in place and provide a construction by which the trolley or roller can be readily removed for repairs, &c.

16 designates a helical spring, one end of which is attached to a hook projecting from the head 1 and the other end is connected to a cord or flexible connection 17, extending through an opening therefor in the bracket 75 4 up between the rollers or pulleys 5, and attached at its other end to the arm 10 of the disk 8. This spring and its connection with the arm 10 acts to normally hold the grooved roller or trolley on the proper line with respect to the pole.

The trolley hereinbefore described is effective in operation, as the stock of the grooved roller being pivoted to the head permits said roller to be turned freely and follow the wire 85 when making a curve, the tension of the spring 16 being only sufficient to normally hold the roller in a certain position to facilitate the operation of moving the roller in engagement with the wire.

Having thus described my invention, I do not wish to be limited to the particular construction and arrangement of the parts herein shown, but reserve the right to modify such construction within the spirit and scope of my 95 claims.

I claim—

1. In a trolley, the combination with the head having an annular flange, an axial recess and an annular groove, the latter being 100 located between the recess and flange; of the stock bearing at its lower end in the axial recess, a disk secured to said stock and having an arm projecting through a slot in the an-

annular flange, antifriction-balls interposed between the disk and annular groove of the head; together with a spring, a cord connecting the spring to the arm of the disk, and guides between which the cord passes, substantially as shown and for the purpose set forth.

2. In a trolley, the combination with the head having an annular flange and a cap secured thereto, of the stock of the roller bearing in said cap a disk secured to said stock and provided with a projecting arm, balls interposed between the disk and head; together with the spring, a cord connecting said spring to the arm, and guides between which the cord passes, substantially as shown, and for the purpose set forth.

3. In a trolley, the combination with the head, of the roller-stock pivotally supported on said head, an arm projecting from the stock, a spring connected to the head, and a

cord or flexible connection extending from the spring to the arm; together with guide-rollers between which the cord passes, substantially as shown and for the purpose set forth.

4. In a trolley, the combination with the curved roller-stock, of the roller having an axle the ends of which lie flush with the outer surface of the stock, spring-plates secured to the stock to overlie the ends of the axle, and lugs with which notches in the ends of the plates engage, substantially as shown and for the purpose set forth.

In testimony whereof I have signed this specification in the presence of two subscribing witnesses.

GEORGE A. HALL.
